Fig. 3.

Fig. 5.

A cross-sectional diagram of a mechanical assembly, likely a gear or sprocket. The diagram shows a central shaft with a gear at the top. Below the gear, a series of pins or teeth are arranged in a curved pattern. The assembly is labeled with numbers: 44, 45, 46, 47, 48, 49, 50, and 99. Number 44 is on the left, 45 is at the bottom, 46 is on the right, 47 is above 45, 48 is above 47, 49 is above 48, 50 is above 49, and 99 is at the top left. There are also some smaller numbers and letters like 1.1. and 1.1.1. near the bottom right.

UNITED STATES PATENT OFFICE.

ELZA T. S. CLIFFE, OF MANSFIELD, OHIO.

SHOE-SHINING MACHINE.

1,289,117.

Specification of Letters Patent. Patented Dec. 31, 1918.

Application filed May 13, 1918. Serial No. 234,164.

To all whom it may concern:

Be it known that I, ELZA T. S. CLIFFE, a citizen of the United States of America, residing at Mansfield, in the county of Rich- 5 land and State of Ohio, have invented cer- tain new and useful Improvements in Shoe- Shining Machines, of which the following is a specification, reference being had therein to the accompanying drawings.

10 This invention relates to a shoe cleaning and shining machine, and more particularly in to that type of coin controlled machine in which the feet are inserted to have the shoes thereon automatically cleaned, blackened 15 and polished.

My invention aims to provide a safe, durable and compact machine of the above type which may be characterized in the following particulars. First, there are novel endless brushing elements that are brought into 20 action to remove dirt, dust and foreign matter from the shoes, and novel means is employed, in a manner as hereinafter set forth for tilting or oscillating the endless brush 25 elements so that the exposed portion of the shoes will be thoroughly operated upon by the brush elements to clean the shoes preparatory to receiving polish. Irrespective 30 of the tilting or oscillatory movement of the brush elements, said elements are maintained in motion, and this is accomplished by a mechanism that is positive in its action and free from injury under ordinary 35 circumstances.

Second, the machine includes what may be termed pneumatic means for applying a liquid blackening to the shoe, the blackening being sprayed on the sides of the shoe so that the edges of the shoe sole and the 40 upper will receive a thin film of the blackening liquid. The liquid is applied by ejectors receiving a supply of air from an air pump operated in connection with the machine, and this pump also supplies air for 45 drying the blackening, thus preventing the brushes from being laden with blackening and in all probability rendered useless for polishing purposes.

Third, my machine is characterized by 50 electrical controlling devices so that certain operations may take place in sequence and the machine be restored to normal conditions after a pair of shoes has been operated upon.

55 The above briefly outlines a machine

which includes the following principal elements—namely, a housing, foot rest, motor and shafting; brush cases and raising and lowering mechanism thereof; tilting or oscillating mechanism for the brush cases; 60 blackening and air applying apparatus; electric controlling devices for the blackening and air applying apparatus, and coin and electric controlling devices of the machine. These elements will be hereinafter 65 separately and specifically described in detail, together with the novel arrangement and objects accomplished from such a combination of elements.

Reference will now be had to the drawings, wherein—

Figure 1 is a longitudinal sectional view of a portion of the machine, showing by dotted lines different positions the tiltable or oscillatory brush cases may assume; 75

Fig. 2 is a cross sectional view of the machine, directly behind the front wall thereof, looking at the greater portion of the machine;

Fig. 3 is a plan of a portion of the machine, showing in dotted lines the blackening and air applying apparatus;

Fig. 4 is an enlarged horizontal sectional view of a portion of one of the brushes;

Fig. 5 is a cross sectional view of a portion of a brush casing, 85

Fig. 6 is a plan of the greater part of the machine with the housing thereof removed, and

Figs. 7 and 8 show detail views of a belt 90 shifting device that may be used as part of the machine.

In describing my invention by aid of the views above referred to, I desire to point out that the same are merely illustrative of an 95 example whereby my invention may be put into practice, and I do not care to confine myself to the precise construction or arrangement of parts, other than defined by the appended claims.

100 In the drawings, the structural elements have been shown as nearly in proportion as possible, and in describing the machine in detail, it is thought best to refer to the various elements or organization under those captions enumerated above.

Housing, foot rest, motor and shafting.

The housing, is substantially rectangular and includes a base 1 and particularly a 110

top wall 2, said top wall having oblong openings 3 which provide clearance for brush cases. Above the opening 3 is a casing 4 and the top wall of said casing has 5 the front edge thereof recessed, as at 6, to provide clearance for the ankles of a person whose shoes are to be cleaned and polished in the machine. The top wall 5 of the casing 4 is also cut away, as at 7, for 10 horizontally hinged or pivoted shutters or shields 8, which are held normally opened by coiled springs 9, connecting the shields 8 and the top wall 5 of the casing 4. The hinges which connect the shields 8 to the 15 casing 4 have the pintles 10 thereof provided with cranks 11, and when placing the feet in position said cranks are engaged by the shoes and shifted rearwardly, as indicated by dotted lines in Fig. 3, thus closing 20 the shields 8 above the shoes. The shields 8 are recessed, as at 12, so as to coöperate with the recess 6 of the top wall 5 in providing clearance for the ankles. The shields 8 are adapted to prevent trousers, skirts or 25 clothing from being splashed with blackening and serve as an air deflector, said shields automatically assuming an open position as the feet are removed from the casing 4.

In the housing, on the base 1 thereof, are 30 uprights 13 each provided with a footrest 14 in the openings 3, said rests correctly positioning shoes or footwear to be cleaned and polished. The uprights 13 are preferably located at the forward end of the housing and at the rear end of the housing, on 35 the base 1, is an electric motor 15 adapted to be operated from a suitable source of electrical energy, such as an ordinary electric lighting circuit (not shown).

On the base 1 are a set of A-frames 17, a set of cam frames 18, and another set of A-frames 19. The A-frames 19 are adjacent the motor 15 and journaled in said A-frames 40 is a power transmission shaft 20 provided with a belt-wheel 21 in a vertical plane with a belt-wheel 22 on the armature shaft 23 of the motor 15 and trained about the belt-wheels 21 and 22 is a belt 24.

The cam frames 18 have bearings 25 and 50 26 for crank shafts 27 and 28 respectively, the crank shaft 27 having a set of cranks 29 and the crank shaft 28 a set of cranks 30.

On the shafts 20 and 27 are belt-wheels 55 31 and 32 respectively, and trained about said belt-wheels is a belt 33.

On the shafts 20 and 28 are belt-wheels 34 and 35 respectively and trained about said belt-wheels is a belt 36.

Another shaft 37 is journaled in the A-frames 17 and on the end of said shaft is 60 a belt wheel 38 alining with a belt wheel 39 on the shaft 20. Over the belt wheels 38 and 39 is trained a belt 40.

From the above it will be noted that

power may be transmitted from the electric motor to the shafts 20, 28, 27 and 37, and while I have herein referred to belt wheels and belts, it is obvious that the sprocket wheels and chains or other power transmitting mechanism can be employed. 70

Brush cases and raising and lowering mechanism thereof.

Below each footrest 14 is a hollow case 75 41 having an opening 42 therethrough that conforms in contour to the marginal edges of a shoe sole, said opening providing clearance for the shoe on the foot rest, when the case 41 is raised, tilted or oscillated. Each 80 case 41 has the inner side thereof open and the top and bottom wall provided with guides 42^a for rollers 43 carried by the upper and lower ends of links 44 which are connected and compose an endless brush 85 chain. Each link has the outer face thereof provided with bristles or a brush 45 and the inner face of each link has teeth 46 adapted to mesh with worms 47 in the hollow sides 90 of the cases 41. The worms 47 are mounted on shafts 48 journaled in bearings 49, carried by the outer side wall of each case, and on the shafts 48 are worms 50 that rest on and mesh with gear wheels 51. There 95 are four of the gear wheels 51 all mounted on a common shaft 52, journaled in bearings 53 having arms 54 slidable in guides 55, carried by the A-frames 17.

On the shaft 52 are gear wheels 56 meshing with large gear wheels 57 mounted on 100 the shaft 37, and said large gear wheels have depressed portions 58, as best shown in Fig. 1, which cause the shaft 52 to be raised and lowered and at the same time establish a driving relation between the shaft 52 and the shaft 37, so that the endless brush chains may be caused to travel in the cases 41. 105

Each case 41, intermediate the ends thereof and at one side wall has a stud 59 extending into a segment slot 60 provided therefor in a bracket 61, carried by each of the bearings 53. 110

Tilting or oscillatory mechanism for the brush cases. 115

The cam frames 18 have cam grooves or slots 62 for anti-frictional rollers 63 on the ends of a shaft 64 which is adapted to be 120 moved throughout the cam grooves of the cam frames 18. The shaft 64 has sets of flanged collars 65 and 66, the former adapted to be engaged by the cranks 29 of the shaft 27, and the latter by the cranks 30 of 125 the shaft 28, the cranks 29 being employed to partially elevate the shaft 64 and cranks 30 to lower said shaft.

Loose on the shaft 64 are the lower ends 67 of pitmen 68 said pitmen having the 130

upper ends thereof pivotally connected, as at 69, to the rear ends of the cases 41. The rear ends of the cases are also connected by coiled retractile springs 70 to the casing 4, and the retractile force of said springs is sufficient to restore said cases to normal horizontal positions, as will hereinafter appear.

10 *Blackening and air applying apparatus.*

On the top wall 2, within the casing 4, or at some convenient location, is a main reservoir 71 adapted to contain a blackening liquid, which is fed by gravity or siphoned 15 into auxiliary reservoirs 72 by pipes or tubes 73. The auxiliary reservoirs are secured to the bottom side of the top wall 2 contiguous to the front and rear ends of the openings 3, and extending through said auxiliary 20 reservoir and communicating therewith are air supply pipes 74. The pipes 74 extend to nozzles 75 located in or on the marginal edges of the top wall openings 3, as shown in Fig. 3, said nozzles being distributed so 25 as to direct blackening and air to the exposed portions of the shoe.

The air supply pipes 74 are in communication with a conventional form of air pump 76, supported from one of the A frames 19, 30 below the end of the shaft 20, so that the end of said shaft may be provided with an eccentric 77 connected to the pump piston 78 for operating the same. The pump 76 has an air intake connection 79 and a check valve 35 exhaust or safety valve 80.

The air supply pipes 74, within the auxiliary reservoirs 72 have valves controlling communication between said air supply pipes and said auxiliary reservoirs, and the 40 stems 81 of the valves protrude from the auxiliary reservoirs and are provided with cranks 82. One end of each crank has a weight 83 that maintains the valve in the auxiliary reservoir normally closed, and the 45 opposite end of the crank serves as an armature 84 and is limited in its movement in one direction by a suitable stop on the auxiliary reservoir.

On the air supply pipes 74, contiguous to 50 the air pump 76, is a valve 85 that is normally closed by a weighted crank 86 and one end of the crank serves as an armature.

55 *Electric controlling devices for the blackening and air apparatus.*

On the base 1, adjacent one end of the shaft 27, are switches 87 and 88 that are normally open, the switch 87 controlling the supply of blackening to the nozzle 75, and 60 the switch 88 controlling the supply of air. The switch 87 has wires 89 tapped into the lead-in wires to the motor 15 and the wires 89 are also connected to electro-magnets 90 on the auxiliary reservoirs 72 adjacent the armatures 84, so that when said electro-magn-

nets are energized, the armatures 84 will be attracted to open the valves within the auxiliary reservoirs 72, thereby permitting air to remove blackening from the auxiliary reservoirs and discharge the same at the nozzles 75.

The air switch 88 is connected by wires 91 to an electro-magnet 92 adjacent the valve 85, said electro-magnet and said switch being in circuit with the lead-in wires to the 75 motor 15. When the electro-magnet 92 is energized the valve 85 is opened, thus permitting the supply of air to flow toward the auxiliary reservoirs 72.

To actuate the switches 87 and 88 and close 80 and open the same in proper sequence, the end of the shaft 27 has a cam wheel 93 provided with cams 94 and 95, the former being of less length than the latter. The cams 94 and 95 are adapted to simultaneously close 85 the switches 87 and 88, but the switch 88 is maintained closed for a greater period of time than the switch 87, due to the length of the cam 95. It is therefore possible to inject or force a quantity of blackening from 90 the auxiliary reservoirs on to the shoes and then cut off the supply of blackening, with the air continuing whereby the blackening applied to the shoes will be dried thereon.

95 *Coin and electric controlling device of the machine.*

It is necessary that there be a cessation in the operation of a portion of the machine while blackening is being applied to the 100 shoes and dried thereon, so the shaft 37 has the other end thereof provided with a clutch 96 operated by a lever 97 pivoted on an electro-magnet 98 supported from one of the A-frames 17. One end of the lever 97 serves 105 as an armature for the electro-magnet 98 and said armature is normally held retracted by a coiled spring 99. The electro-magnet 98 is in circuit with the motor 15 and is connected by wires 100 to a normally open 110 switch 101 located below a cam wheel 102 on the shaft 27, said cam wheel having a cam 103 adapted to close the switch 101. By reference to Fig. 1, it will be observed that the cam 103 is brought into action simultaneously with the cams 94 and 95, consequently the switch 101 will be closed to energize the electro-magnet 98, actuate the lever 115 97 and disengage the clutch 96, so that that portion of the machine operated through the 120 medium of the shaft 37 is discontinued until after blackening and air have been applied to the shoe.

Another switch is located on the base 1 of the machine, said switch being in the form 125 of a knife switch having a knife carried by pivoted spring retracted lever 105 actuated by a solenoid 106 to close the knife switch, which is in circuit with the motor 15 and controls the operation of the same. The 130

solenoid 106 is connected by wires 107 to contact members 108 and 109. The contact member 108 is in a coin chute 110 located in the upper part of a housing and adapted to have a coin 111 deposited therein. The contact member 109 is pivotally supported and held by a spring with one end of said contact member extending into the coin chute to be engaged by the coin 111 when deposited therein, said coin connecting or bridging the contact members 108 and 109 thereby closing the electric circuit for the solenoid 106.

The knife lever 105 of the knife switch 104 has a lug or stop 112 adapted to engage in a notch provided therefor at the periphery of a wheel 113 mounted on the shaft 27, and it is this electric coin control mechanism that locks and unlocks the machine after and before its use.

20 In lieu of the clutch 96 and its electrical operating means, I may employ the automatic belt shifting device shown in Figs. 7 and 8. The shaft 37 is arranged to slide in its bearings with the gear wheels 56 of sufficient width to at all times mesh with the gear wheels 57. On the end of the shaft is an idle belt wheel 120 adapted to receive the belt 40, when the shaft 37 is shifted, and to accomplish this, the frame 17 has a cam member 121 normally engaged by a shifting member 122 fixed on the shaft 37, said shifting member being held in engagement with the cam member 121 by a forked lever 123 pivotally connected to the frame 17 and 25 furthermore connected thereto by a coiled retractile spring 124. A forked arm 125 on the frame 17 prevents the belt 40 from moving sidewise during the shifting of the shaft 37.

30 The cam member 121 is proportioned and shaped as to momentarily cause a cessation in the operation of the brushes while polish is applied.

45 General operation.

By reference to Fig. 1, it will be noted that while there is a cessation in the operation of the machine, that the depressed portions 58 of the large gear wheels 57, permit 50 of the bearings 53 being in lowered positions, therefore the cases 41 will be held below the foot rests 14 and permit of a person easily placing his or her feet on the foot rests.

55 When the coin 111 is deposited in the machine, a circuit is temporarily established through the solenoid 106 and the cam wheel 113 is released. While the coin 111 is maintaining a closed circuit through the contact members 108 and 109, preparatory to dropping out of the chute 110, the knife switch 104 has been closed thereby starting the motor 15, said motor through its power transmission mechanism moving the wheel 113 60 sufficiently to prevent the lug or stop 112 en-

tering its notch in the wheel 113, until said wheel has made one complete revolution. The lug or stop 112 will be held against the periphery of the wheel 113 ready to stop said wheel at the end of one complete revolution.

The motor 15 having been placed in operation, the large gear wheels 57 are revolved and the bearings 53 are elevated to raise the cases 41 to horizontal dot and dash line 75 positions shown in Fig. 1. During the raising of the cases 41 the endless brushes therein are set in motion and the sides of the shoes will be cleansed of dirt, dust and such other matter as can be removed by the 80 brushes.

According to the transmission mechanism shown, the shafts 37 and 20 are driven at the same speed, but the shafts 27 and 28 are driven at a reduced speed, approximately 85 half that of the former. It is therefore possible for the large gear wheels 57 to make one complete revolution before any of the remainder of the machine is placed in operation, and it is during this complete revolution that the cases 41 are raised to clean the shoes and then lowered to normal position.

Assuming that this operation has taken place, the cams 103, 94 and 95 are brought into action in conjunction with the switches 95 101, 87 and 88. The switch 101, through the medium of the solenoid 98 and the clutch 96 causes a cessation in the raising and lowering mechanism of the cases 41, also the brushes therein, and the blackening and air 100 supply apparatus is brought into action. As previously pointed out, the switches 87 and 88 are simultaneously closed, thereby opening the valve 85 of the air supply and the valves within the auxiliary reservoirs 72, 105 allowing the pressure of air to eject blackening from the nozzles 75 to the shoes. When a predetermined quantity of blackening has been applied, the valves within the auxiliary reservoirs 72 are closed by the 110 opening of the switch 87, which deenergizes the electro-magnets 90 and permits of the weighted cranks 82 shutting off the supply of blackening. The air, however, is permitted to flow and is discharged by the nozzles 115 75 against the shoes to dry the blackening thereon. This operation continues until the cam 95 releases the switch 88, deenergizing the electro-magnet 92, and permitting the weighted crank 86 to close the valve 85.

120 By this time the cam 103 has permitted the switch 101 to open, deenergizing the electro-magnet 98, and permitting the lever 97 to throw in the clutch 96, thereby establishing a driving relation between the motor 125 15 and the shaft 37.

The cases 41 are again raised and the brushes therein set in motion and during this operation the cases 41 are tilted through the medium of the cranks 29 and 30, shaft 130

64, pitmen 68 and springs 70. The cranks 29 being swung about engage the flange collars 65 and shift the shaft 64 to the upper ends of the cam grooves 62. As the cranks 5 29 pass out of engagement with the flange collars 65, the cranks 30 engage in the flange collars 66 of the shaft 64 and shifts said shaft to the lower ends of the cam grooves 62 from which position the shaft 64 is 10 stored to normal position by the springs 70 connected to the rear end of the cases 41.

The tilting of the cases 41 is permissible through the medium of the brackets 61 with the studs or trunnions 59 extending into the 15 slots 60 also by reason of the worm and gear power transmission between the shaft 52 and the endless brushes 45. By tilting the cases 41 the uppers of the shoe are polished, as well as the heel and other parts adjacent 20 to the sole of the shoe. After this operation the cases 41 are eventually lowered; the lug or stop 112 snapped into the notch of the wheel 113, thereby breaking the circuit of the motor 15 and causing a cessation in 25 the operation of the machine.

As the shoes are removed from the rests 14 the springs 9 open the shields 8 and the machine is now in condition for cleaning and shining another pair of shoes.

30 What I claim is:—

1. A shoe shining machine comprising cases adapted to surround shoes, movable brushes in said cases, means adapted for simultaneously raising and lowering said 35 cases and moving the brushes therein, means adapted for supplying blackening and air to the shoes while said cases are lowered, and means adapted for tilting said cases when said cases are elevated.

40 2. A shoe shining machine comprising a shoe rest, a blackening and air supplying apparatus adjacent said shoe rest and adapted to successively apply blackening and air to shoes on said rest, electrically controlled 45 valvular means adapted to cause a cessation in the blackening of the shoes and a continuation of the application of air thereto, and means tilttable relative to the shoes adapted for polishing the shoes after the application 50 of air.

55 3. In a shoe shining machine, the combination of cases adapted to surround shoes, movable endless brushes in said cases, means including gears adapted to simultaneously raise and lower said cases relative to the shoes, and impart movement to said brushes, pitmen connected to said cases, a shaft connected to said pitmen, cranks adapted to impinge against said shaft to raise and lower 60 said shaft and impart a tilting movement to said cases, and means adapted for operating said cranks in timed relation to the raising and lowering of said cases.

65 4. In a shoe shining machine, the combination of cases adapted for surrounding shoes,

brushes in said cases, means adapted to simultaneously raise and lower said cases and impart movement to said brushes, nozzles adjacent said cases and adapted to successively apply blackening and air to the shoes 70 when said cases are lowered, electric means adapted to control the supply of blackening and air to said nozzles in timed relation to the raising and lowering of said cases, and means including pitmen and springs adapted 75 for tilting said cases in timed relation to the application of blackening and air to the shoes.

5. In a shoe shining machine, the combination of cases adapted to surround shoes, movable brushes in said cases, means including gears adapted for raising and lowering said cases and setting said brushes in motion, reservoirs adjacent said cases containing blackening and in communication with a supply 80 of air under pressure adapted to eject blackening from said reservoirs, on to the shoes when said cases are lowered, electric means controlling the supply of air under pressure 85 for ejecting blackening from said reservoirs, electric means controlling the ejection of blackening from said reservoirs independent of the electric means controlling the air supply, and means operated in timed relation to the raising and lowering of said cases 90 adapted to control both of said electric means.

6. In a shoe shining machine, the combination of cases adapted to surround shoes, movable endless brushes in said cases, means adapted for simultaneously operating said brushes and raising and lowering said cases, means adapted for supplying blackening and air to the shoes when the cases are lowered, means adapted for tilting said cases when 100 said cases are raised, and a motor adapted for operating both of the above mentioned means.

7. In a shoe shining machine, the combination of cases adapted to surround shoes, movable brushes in said cases, means adapted to simultaneously raise and lower said cases and maintain said brushes in motion so that said cases may approach the shoes and recede therefrom, means adapted for applying blackening to the shoes after said cases have receded, and means controlling the raising and lowering means of said cases so that said cases may approach the shoes twice during 110 one cycle in the operation of said machine.

8. In a shoe shining machine, the combination of cases adapted to surround shoes, movable endless brushes in said cases, means adapted for raising and lowering said cases, means adapted for moving said brushes while said cases are raised, means adapted for tilting said cases, and means controlling the raising and lowering and tilting means of said cases so that said cases are raised 120 and lowered twice during the cycle of op- 125

eration of said machine and said cases tilted while said cases are raised in the last half of the cycle of said machine operation.

9. In a shoe shining machine, the combination of cases adapted to surround shoes, movable endless brushes in said cases, movable brackets adjacent said cases, trunnions carried by said cases and extending into said brackets and slidably therein, means including gears adapted for raising and lowering said brackets, means including worms and

other gears for imparting movement to said brushes, and means adapted for applying blackening under pressure to the shoes while said cases are lowered.

15

In testimony whereof I affix my signature in the presence of two witnesses.
